Primary Examiner — Cary M Robinson

CLAIM

The ornamental design for a display screen with graphical user interface as shown and described.

DESCRIPTION

The sole FIGURE is a front view of a display screen with graphical user interface of our new design.

The broken line at the periphery of the FIGURE illustrates the display screen, and the remaining broken lines, including the broken line showing of text and numbers, illustrate portions of the graphical user interface. None of the broken lines form part of the claimed design.

1 Claim, 1 Drawing Sheet
